CLAIM

The ornamental design for a drainage bag outlet including closure, as shown and described.

DESCRIPTION

FIG. 1 is a top, front perspective view of a drainage bag outlet including closure embodying our new design;

FIG. 2 is a front view thereof;

FIG. 3 is a rear view thereof;

FIG. 4 is a side view thereof as seen from the right-hand side of FIG. 2;

FIG. 5 is a side view thereof as seen from the left-hand side of FIG. 2;

FIG. 6 is a top view thereof; and,

FIG. 7 is a bottom view thereof.

Portions of the drainage bag outlet including closure shown in phantom lines in FIGS. 1-7 form no part of the claimed design.

1 Claim, 5 Drawing Sheets
